UNITED STATES PATENT OFFICE.

ARTHUR W. ANKENY, OF INDIANA, PENNSYLVANIA.

DESIGN FOR A WALL-DECORATING FABRIC OR SIMILAR ARTICLE.

Application filed September 5, 1924. Serial No. 10,686. Term of patent 7 years.

To all whom it may concern:

Be it known that I, ARTHUR W. ANKENY, a citizen of the United States, residing at Indiana, in the county of Indiana and State of Pennsylvania, have invented a new, original, and ornamental Design for Wall-Decorating Fabric or Similar Article, of which the following is a specification, reference being had to the accompanying drawing, forming a part thereof.

The figure is a face view of a piece of wall decorating fabric or similar article showing my new design.

I claim:

The ornamental design for a wall decorating fabric or similar article, as shown.

ARTHUR W. ANKENY.
